INCINERATOR COMBINED HOPPER AND
DOOR MEANS

Clayton Nelson Tozer, Julian, Calif.

Application August 13, 1943, Serial No. 498,596

4 Claims. (Cl. 193—34)

My invention relates to a combined hopper and door means for incinerators, more particularly adapted for home or school use and the objects of my invention are:

First, to provide combined hopper and door means of this class with provision for readily receiving bulk trash of all kinds to be burned;

Second, to provide a combined hopper and door means of this class with provision for shielding the trash from the wind while it is being dumped into the hopper;

Third, to provide a combined hopper and door means of this class wherein the doors are used when opened to form a part of the receiving hopper;

Fourth, to provide a combined hopper and door means of this class which may be fitted into the conventional incinerator with a side opening with but slight changes;

Fifth, to provide a novelly constructed handle and heat shield for incinerator doors;

Sixth, to provide a combined hopper and door means of this class with a slanting portion with overhanging cover to shed rain and make the hopper opening easily accessible; and

Seventh, to provide a combined hopper and door means of this class which is very simple and economical of construction, easy to operate, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a sectional view of my combined hopper and door means taken from the line 1—1 of Fig. 2 with the doors in closed position and showing the incinerator fragmentarily; Fig. 2 is a front elevational view thereof shown fragmentarily and Fig. 3 is a fragmentary top view taken from line 3—3 of Fig. 1 with the doors closed.

Similar characters of reference refer to similar parts and portions throughout the several views of the drawing;

The incinerator body 1, hopper frame 2, shield member 3, doors 4 and 5, inclined hopper front member 6, hopper side walls 7, grate 8, door handles 9, and ash door 10 constitute the principal parts and portions of my incinerator combined hopper and doors means.

The incinerator 1 is preferably made of cement or brick and is provided with a rectangularly shaped front side opening 1a into which is fitted the frame 2 and secured by plaster or otherwise. 5 This frame member 2 is an angular member with one member extending into the opening 1b of the incinerator 1 and the other member 2a fitting against the front side thereof, as shown best in Fig. 1 of the drawing. Secured to this angle member 2 and extending forwardly and upwardly on an angle therefrom is the shield member 3 which extends across the front of the incinerator above the opening 1a, the side walls of which extend upwardly and outwardly on an angle, as 10 shown best in Fig. 2 of the drawing. It is provided at each end with a forwardly extending tapered flange portion 3a. This forwardly extending flange portion 3a serves as a stop for the doors when opened to form a portion of the hopper when receiving trash to be burned. This frame 2 is provided with downwardly extending side strips 2b to which the doors 4 and 5 are hinged by means of hinges 4a and 5a. These members 2b and the doors 4 and 5 are positioned 15 on an angle, as shown in Fig. 1 of the drawing, at a substantial right angle to the shield member 3. The door 5 is provided with a plate 5b which extends past the edge of the door and provides 20 a covering for any expansion space between the edges of the doors 4 and 5. Each of the doors 4 and 5 is provided with a handle 9 which is secured to the door near its front side near the open side as shown best in Fig. 3 of the drawing. 25 It consists of a U-shaped member which is secured at its ends to the door and each is provided with a shield portion 9a which is a plate member spaced slightly from the door, as shown best in Fig. 1 and serves to shield the hand from 30 the heat from the door when opening the same. At the front edge these doors 4 and 5 rest on the upper edge of an inclined hopper front member 6 which extends downwardly and backwardly to a short distance above the level of the grate 35 8, as shown best in Fig. 1 of the drawing. At the lower edge of this member 6 at the front side there is a hinged ash door 10 at its upper side arranged to facilitate the removal of the ashes below the grate at the front side and cans or 40 other coarse material above the grate. The members 2b of the frame member 2 are supported at their upper edges and may be an integral part of the opposite side walls 7 of the hopper. The side members are shaped as shown 45 best in Fig. 1 of the drawing.

The operation of my incinerator combined hopper and door means is substantially as follows:

The doors 4 and 5 when opened rest against the flanges 3a of the shield member 3, thus forming upwardly and outwardly extending tapered side walls of the hopper, while the shield member 3 forms the back portion of the hopper. Thus when the wind is blowing, material may be readily dumped into the hopper shielded by the open doors at the opposite sides and the shield 3 at the back side, and the material when dumped slides downwardly along the inclined portions 6 into the incinerator onto the grate, to be burned after the doors 4 and 5 are closed by using the handles 9.

Though I have shown and described a particular construction, combination and arrangement of parts and portions I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an incinerator combined hopper and door means of the class described, the combination of a frame member secured in the front opening of the incinerator, an inclined wall hopper secured thereto provided with an inclined plane opening at the upper side, a shield member secured to said frame and extending upwardly at substantially a right angle plane to the plane of said opening and provided with inclined flanges at its opposite ends disposed at right angles to said shield, and doors hinged on the side walls of said hopper at their opposed outer sides and arranged to meet substantially at the middle of said opening when closed and arranged to stop and rest when opened against said inclined flanges on said shield.

2. In an incinerator combined hopper and door means of the class described, the combination of a frame member secured in the front opening of the incinerator, an inclined wall hopper secured thereto provided with an inclined plane opening at the upper side, a shield member secured to said frame and extending upwardly at substantially a right angle plane to the plane of said opening

and provided with inclined flanges at its opposite ends disposed at right angles to said shield, a door hinged on the side walls of said hopper at their opposed outer sides and arranged to meet substantially at the middle of said opening when closed and arranged to stop and rest when opened against said inclined flanges on said shield, said frame engaging the inner side of the front wall surrounding the incinerator opening.

3. In an incinerator combined hopper and door means of the class described, the combination of a hopper including straight side walls with inclined plane upper edges and an inclined plane front side wall and provided with an inclined plane opening at its upper side, a pair of doors hinged at their opposed outer sides to said side walls at the upper edge arranged to meet at the middle of said hopper on the inclined plane upper side and arranged to form the side wall opening of said hopper when opened, a shield member positioned at substantially a right angle plane to the plane of the opening in the upper side of said hopper provided with extended tapered ends tapering outwardly at its upper side and provided with flanges extending forwardly at right angles to said shield at the opposite ends thereof to form stops and supports for said doors when opened.

4. In an incinerator combined hopper and door means of the class described, the combination of a hopper including straight side walls with inclined plane upper edges and an inclined plane front side wall and provided with an inclined plane opening at its upper side, a pair of doors hinged at their opposed outer sides to said side walls at the upper edge arranged to meet at the middle of said hopper on the inclined plane upper side and arranged to form the side wall opening of said hopper when opened, and a shield member positioned at substantially a right angle plane to the plane of the opening in the upper side of said hopper provided with extended tapered ends tapering outwardly at its upper side and provided with flanges extending forwardly at right angles to said shield at the opposite ends thereof to form stops and supports for said doors when opened, said hopper side walls being supported by an angle shaped frame member fitted into the opening of the incinerator.

CLAYTON NELSON TOZER.
